United States Patent Office

Des. 185,435
Patented June 9, 1959

185,435

FRYING PAN

Clifford Hockley, Greeley, Colo.

Application May 12, 1958, Serial No. 50,834

Term of patent 14 years

(Cl. D44—1)

Fig. 1

Fig. 2

Fig. 1 is a top plan view of a frying pan showing my new design; and

Fig. 2 is a cross-sectional view taken on line 2—2 of Fig. 1.

I claim:

The ornamental design for a frying pan, as shown.
